United States Patent Office

Des. 211,422
Patented June 11, 1968

211,422

FRONT COVER FOR A PRESS

Millard K. Long, North Canton, Ohio, assignor to E. W. Bliss Company, Canton, Ohio, a corporation of Delaware

Filed Sept. 22, 1967, Ser. No. 8,695

Term of patent 14 years

(Cl. D63—1)

FIG. 2

the front cover.

The dominant features of my design reside in the portions shown in full lines.

I claim:

The ornamental design for the front cover for a press,
as shown and described.
